UNITED STATES PATENT OFFICE.

LUTHER J. ADAMS, OF LEOMINSTER, MASSACHUSETTS.

SEESAW.

SPECIFICATION forming part of Letters Patent No. 253,571, dated February 14, 1882.

Application filed September 23, 1881. (Model.)

To all whom it may concern:

Be it known that I, LUTHER J. ADAMS, of Leominster, in the county of Worcester and State of Massachusetts, have invented certain 5 new and useful Improvements in Seesaws; and I do hereby declare the following to be a full, clear, and exact description of the invention, such as will enable others skilled in the art to which it pertains to make and use it, reference 10 being had to the accompanying drawings, which form part of this specification.

My invention relates to an improvement in seesaws; and it consists, first, in making the seesaw out of a number of different pieces, 15 which are hinged together so that the seesaw can be folded up when not in use, and thus be packed into very small space; second, in making the seesaw out of a number of different pieces, which are hinged together, and attaching 20 to the base a hinged or pivoted brace, which can be raised upward, so as to catch under the center of the hinged top, and thus support the top in a raised position, ready for use, as will be more fully described hereinafter. 25 The object of my invention is to provide a seesaw which can be folded up either for transportation or so as to occupy but very little space when not in use, and thus enable children to keep a seesaw in the house without 30 having it take up too much room or require any permanent fixture.

Figure 1 is a side elevation of my invention complete. Fig. 2 is a vertical section of the same. Fig. 3 is a side elevation of the seesaw 35 folded together.

A represents the base, which may be of any desired length or width, and to which the two supporting boards B are hinged or pivoted, as shown. These boards have secured to their 40 outer ends the hinges C, which serve to unite them with the outer ends of the two boards D, (upon the outer ends of which the children sit while they seesaw up and down,) and have their inner ends hinged together by means of the hinge F.

Jointed loosely upon the top of each end of the base is a supporting rod or brace, G, which is preferably bent into the form shown in Fig. 2, and which catches in a notch which is formed 45 equally in the end of each of the two boards. When this brace is raised into a vertical po-

sition after the seesaw has been opened out, the two ends are supported in such a manner as to form, as it were, one solid continuous board. The ends of the two supporting boards or braces being hinged or pivoted to the base-piece and the metallic brace being pivoted upon the top of the base, it will readily be seen that the children seated on the end of the top board can seesaw with perfect ease and 55 freedom.

When the seesaw is no longer needed or when it is to be packed up for transportation, the metallic brace G is folded down upon either one of the bracing-boards, the two top 60 boards have their inner ends forced down, and the seesaw then assumes the position shown in Fig. 3. While folded together the outer ends of the boards can be held securely together by means of a spring, wire, or band, I, 65 as shown.

Where the seesaw is to be used in the house or any place where the room is limited, after having been used the seesaw can be folded up, as shown, and stood up like a post, of which 70 the base forms the foot, or can be laid down upon its side, as may be most convenient. By means of this construction these seesaws can be used in the house, can be sent out to pleasure-grounds at picnics, and enjoyed by the 75 children in many ways where the common form of seesaw could not be used at all.

Having thus described my invention, I claim—

1. In a seesaw, the combination of the board 80 D with rocking supports, to which the board is loosely attached, substantially as shown.

2. The combination of the base, the two supporting-boards B, the two hinged top boards, and the metallic supporting-brace, substantially 85 as described.

3. In a seesaw, the combination of the board D, jointed at its center, with the hinges C, the supports B, loosely connected to the base A, and the pivoted brace G, the parts being adapted to be folded together, substantially as specified. 90

In testimony whereof I affix my signature in presence of two witnesses.

Witnesses: LUTHER J. ADAMS.
